Patented Aug. 5, 1919.

Inventor

JOHN DOMINA

By *Watson E. Coleman*

Attorney

UNITED STATES PATENT OFFICE.

JOHN DOMINA, OF CHICAGO, ILLINOIS.

FAN.

1,312,023.

Specification of Letters Patent.

Patented Aug. 5, 1919.

Application filed January 19, 1917. Serial No. 143,338.

To all whom it may concern:

Be it known that I, JOHN DOMINA, a subject of the King of Italy, residing at Chicago, in the county of Cook and State of Illinois, have invented certain new and useful Improvements in Fans, of which the following is a specification, reference being had to the accompanying drawings.

This invention relates to certain improvements in fans and has relation more particularly to a device of this general character of a rotary type; and it is an object of the invention to provide a device of this general character having novel and improved means whereby the same may be readily and conveniently operated through the medium of a spring motor.

It is also an object of the invention to provide a device of this general character with novel and improved means whereby a rotation of the fan carrying or driven shaft may be readily controlled.

The invention consists in the details of construction and in the combination and arrangement of the several parts of my improved fan whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be the better understood, I will now proceed to describe the same with reference to the accompanying drawings, wherein

Fig. 1 is a view partly in side elevation and partly in vertical section of a fan constructed in accordance with an embodiment of my invention;

Fig. 2 is a view in rear elevation of the device as herein embodied with the rear plate or head removed; and

Fig. 3 is a detail fragmentary view partly in elevation and partly in section illustrating certain details of construction as herein disclosed.

As disclosed in the accompanying drawings, B denotes a base plate of predetermined configuration and dimensions and with which is suitably connected an upstanding post or arm 1 having its upper portion 2 substantially cylindrical in form to afford a head for the cylindrical casing C, said casing being secured to the circular portion 2

in any desired manner but preferably through the medium of the brackets 3.

The center of the circular portion 2 is provided with an outstanding bearing 4 in which is rotatably mounted an end portion 60 of the winding shaft 5. The inner end portion of said shaft 5 is rotatably supported by the plate 6 positioned within the casing C and supported in predetermined spaced position relative to the circular portion 2 65 through the medium of the bolts or spacing members 7.

Loosely mounted upon the winding shaft 5 and rotatable therearound is the driven wheel or gear 8 adapted to be rotated by the 70 spring S of a conventional type, the outer end portion of said spring being anchored, as at 9, to a marginal portion of the gear or wheel 8 and having its inner end anchored, as at 10, to the winding shaft 5. 75

The gear or wheel 8 is in mesh with the pinion 11 fixed to the driven or fan carrying shaft 12 rotatably supported by a second outstanding bearing 14 carried by the circular portion 2 at a point preferably 80 above and in vertical alignment with the bearing 4. The shaft 12 is also rotatably supported by the plate 6 hereinbefore referred to.

The shaft 12 is of such a length as to extend beyond the outer end of the bearing 14 and suitably affixed to said outer end portion of the shaft 12 is the fan member F of any ordinary or preferred type.

The shaft 12 has its inner end extending 90 beyond the plate 6 and suitably affixed to said last named extended portion of the shaft 12 is a disk 15 with which is adapted to coact the endwise movable member 16 for controlling the operation of the fan. As 95 herein embodied, the member 16 is threaded, as at 17, through the rear head 18 suitably affixed, as at 19, to the casing C. The portion of the member 16 exterior of the casing C is provided with the crank 20 whereby 100 the requisite rotation may be imparted to the member 16 for adjusting the same into or out of contact with the disk 15. It is thought to be self-evident that the member 16 may be adjusted to hold the shaft 12 105 against rotation under the influence of the spring S or that said member 16 may be so adjusted relative to the disk 15 as to vary the speed at which said shaft 12 may rotate.

As is particularly illustrated in Fig. 1, 110

the inner end portion of the shaft 5 is threaded, as at 21, to afford convenient means whereby the winding member or crank 22 may be operatively engaged therewith, the rear head 18 being provided with an opening 23 through which the engaging portion of the winding member or crank 22 is adapted to be inserted.

The rear portion of the shaft 5 has affixed thereto a ratchet wheel 24 with which coacts the dog or pawl 25 pivotally engaged, as at 26, with the plate 6, said dog or pawl 25 coöperating in a well known manner with the ratchet 24 for holding the shaft 5 against rotation under the influence of the tension of the spring S. The dog or pawl 25 is maintained in requisite engagement with the ratchet 24 through the medium of the retractile member 27 herein disclosed as a conventional coil spring anchored at one end to the dog or pawl 25 at a point intermediate the length of said dog or pawl and secured at its opposite end to a bracket 28 or the like suitably affixed to the plate 6 and preferably through the medium of one of the spacing bolts or members 7.

The ratchet 24 is positioned immediately adjacent the plate 6 and suitably affixed to the shaft 5 adjacent the outer face of the ratchet 24 and in contact therewith is a disk 29 of a diameter in excess of the diameter of the ratchet 24 which serves to hold the dog or pawl 25 against undue lateral movement and whereby the requisite coaction between the dog or pawl 25 and the ratchet 24 is assured.

It is also preferred that a disk 30 be affixed to the shaft 12 and in contact with the outer face of the disk 15, said disk 30 being of a diameter less than the diameter of the disk 15 so that the periphery thereof affords an annular shoulder coacting with the adjacent end portion of the member 16 for holding the inner end portion of said

member 16 against any undue lateral movement inwardly of the disk 15 so that the desired coöperation between the member 16 and the disk 15 is maintained.

From the foregoing description, it is thought to be obvious that a fan constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

A device of the character described comprising a base, an upstanding arm carried by the base, a casing in contact with the upper portion of the arm, brackets secured to the casing and the arm for holding the casing to the arm whereby said arm serves as a head for the casing, a plate positioned within the casing and supported by the arm in predetermined spaced relation relative to the arm, a spring operated driving wheel rotatably supported by the arm and the plate within the casing, a winding and fan shafts rotatably supported by the arm and a braking plate within the casing and operatively connected with the spring operated wheel, and a fanning element carried by the shaft exteriorly of the casing.

In testimony whereof I hereunto affix my signature in the presence of two witnesses.

JOHN DOMINA.

Witnesses:

JOHN T. RACINE,
A. L. FORSBERG.
